UNITED STATES PATENT OFFICE.

JOHN MCCALLUM, OF HAREFIELD, ENGLAND, ASSIGNOR TO THE UNITED ASBESTOS COMPANY, LIMITED, OF LONDON, ENGLAND

PACKING FOR STUFFING-BOXES.

SPECIFICATION forming part of Letters Patent No. 732,579, dated June 30, 1903.

Application filed September 11, 1901. Serial No. 75,034. (No specimens.)

To all whom it may concern:

Be it known that I, JOHN MCCALLUM, a subject of the King of Great Britain, residing at Harefield, in the county of Middlesex, England, have invented new and useful Improvements in Packing for Stuffing-Boxes or the Like, of which the following is a specification.

My invention relates to packings which are made in lengths of fibrous material in combination with metal wire. Hitherto packings of this kind have had the metal combined therewith in the form of plates or wire woven or intermixed in such manner that it has been difficult to bend such packings around piston-rods so as to fit the same closely because the metal would not readily yield to the bending.

The object of this invention is to provide packing of asbestos or other fibrous material and metal wire of very simple construction not liable to the metal becoming detached, and so that it may be very easily bent around a piston-rod, and at the same time the metal will be always kept against the surface of the piston-rod, so as to reduce friction. I attain these objects by constructing packing in the manner illustrated in the accompanying drawings, in which—

Figure 1 is a cross-section of a piece of the packing. Fig. 2 is a longitudinal section at the line A A on Fig. 1, showing the layer of metal wire. Fig. 3 is a view of the face of the packing which is in contact with the piston-rod. Figs. 4 and 5 are cross-sectional and face views, respectively, of a modification of the packing. Figs. 6 and 7 are cross-sectional and face views, respectively, of another modification of the packing; and Fig. 8 is a partial cross-section showing the relation of the piston-rod to the packing.

Like letters indicate similar parts in all the views.

Referring to Figs. 1, 2, and 3, *a* is the fibrous material, which is preferably made up of asbestos or of asbestos together with adhesive or other materials. *b* is the metal, consisting of a wire, preferably of lead or other antifriction metal, arranged in a zigzag form in a longitudinal plane perpendicular to the rubbing-face *a'* of the packing and with the apices of the zigzags *b'* alternately presented toward and away from the rubbing-face and prefer-

ably with the wire as nearly touching as practicable at the points *b*², so that as great a surface of metal as possible is presented to the piston-rod or other moving part to be packed. 55 As shown, the asbestos or fibrous material *a* is first formed as a woven cloth, then folded in several thicknesses, and then bent so as to inclose the metal wire on both sides and around one edge of the layer at *c*. The wire may be 60 secured in the asbestos by adhesive material or by stitching in any convenient way.

Referring to Figs. 4 and 5, in this modification there are two layers of metal wire *b*, each arranged in zigzag or sinuous form, as 65 above described. The asbestos or fibrous material *a* is formed in layers and so arranged that there are two grooves or channels *a'*², in which the metal *b* is inserted, being secured therein in any usual or convenient manner. 70

Referring to Figs. 6 and 7, in this modification there are three layers of metal wire *b*, all arranged in zigzag form in layers perpendicular to the rubbing-face, as described above under Figs. 1, 2, and 3. 75

Although I prefer to arrange the fibrous material in the manner shown, my invention is not confined to such arrangement, as the fibrous material may be arranged and secured in relation to the wire in any other convenient way as found suitable so long as the wire is arranged in a zigzag or sinuous form, as described and illustrated. I do not confine myself either to the number of layers of wire, as any number may be used, according 80 to the thickness of packing required or the quantity of metal it is desired to put into a certain section of packing.

By the above arrangements the metal or wire offers no resistance to the bending of the 90 packing around the piston-rod, while at the same time an almost continuous face or faces of metal is or are presented to the rubbing-surface to diminish friction, and by the metal being in one piece parts of the metal are not 95 liable to become detached during handling of the packing, as is the case when the metal is in many separate pieces.

What I claim, and desire to secure by Letters Patent, is—

1. A packing the combination with fibrous material of a layer of metal wire bent into

zigzag form, the inner apices of the zigzags being arranged to contact with each other and with the piston-rod and arranged in the fibrous material in a plane perpendicular and transverse to the piston-rod substantially as described.

2. As a packing the combination with fibrous material of several layers of metal each layer consisting of a wire bent into zigzag form, the inner apices of the zigzags being arranged to contact with each other and with the piston-rod arranged in grooves in the fibrous material in planes perpendicular and transverse to the piston-rod substantially as described.
- 15 3. As a packing the combination with a layer of metal wire arranged in zigzag form,

the inner apices of the zigzags being arranged to contact with each other and with the piston-rod of fibrous material consisting of a sheet of cloth rolled up into several layers and inclosing the layer of metal wire on both sides and one edge, such layer of wire being arranged in a plane perpendicular and transverse to the piston-rod substantially as described.

In testimony whereof I have signed my name to this specification in the presence of two subscribing witnesses.

JOHN McCALLUM.
